United States Patent Office.

WILLIAM H. SUTHERLAND, OF SEVEN MILE, OHIO.

Letters Patent No. 66,263, dated July 2, 1867.

IMPROVEMENT IN EXTENSION UMBRELLAS.

The Schedule referred to in these Letters Patent and making part of the same.

TO ALL WHOM IT MAY CONCERN:

Be it known that I, WILLIAM H. SUTHERLAND, of Seven Mile, in the county of Butler, in the State of Ohio, have invented a new and useful Improvement in Folding Umbrellas; and I do hereby declare that the following is a full, clear, and exact description of the construction and operation of the same, reference being had to the annexed drawings, making a part of this specification, in which—

Figure 1 is a longitudinal elevation of the umbrella, as folded up.

Figure 2, a perspective view of the umbrella, as extended.

Figure 3, a side view of the different sections of the rib, and the stretcher, as attached to the rib.

Figure 4, a view of the several sections of the stick, particularly an interior view of the second and third sections thereof.

Figure 5, an enlarged view of different sections of the stick, showing the interior construction and operation.

Figure 6, a view of the runner, the raised tablet upon which it rests, and the ferrule by which it is secured.

Figure 7 is a plane view of the upper part of the runner.

Figure 8 is a view of the handle and the section of the stick to which it is attached, with the attachments thereof; and

Figure 9 is a view of the under side of the second and third sections of the rib.

The nature of my invention consists in the construction without springs, and operation of an umbrella of two or three sections of rib, and two, three, or more sections of stick, which, principally by a sliding motion, extends and closes an umbrella of the largest diameter, say four feet, so that it may be shut up and folded within a length of twelve or fourteen inches, and put into the trunk, valise, or pocket. The principle is, of course, applicable also to parasols.

The stick, as shown at fig. 4, is composed of any suitable material, and may be made in two or more sections, *fff*. The first or upper section is a solid rod, the other sections being hollow. *g g g* are small metallic tongues firmly fastened to the inner sides, and traversing nearly the entire length of the hollow sections of the stick, and designed to guide the sections of the stick in the act of distending them, and to aid in securing them when so distended. *ll*, as shown in figs. 4 and 5, are thin metallic bands fastened around the lower ends of the first and second sections of the stick, and of the same thickness as the tongues *g g*. In these bands there is a groove, *j j*, fig. 5, adjusted to receive the tongue *g g* and permit the bands to move freely along its sides. In figs. 4 and 5, *tt* show a pin designed to prevent the too great distension of the sections of the stick. *ss*, in those figures, indicate a notch in band *ll*, into which the upper end of tongue *g g* is turned when the stick is distended and locked, and which is designed to hold it in that position. *uu*, in figs. 4 and 5, represent small metallic collars fastened on the inside of the upper end of the second and third sections of the stick. They are of the same thickness as tongue *g g* and band *ll*, and are designed to make the sections of the stick move equally and smoothly through each other. *kk*, as seen in figs. 4 and 6, are a hollow metallic tablet screwed on to the outside of the upper end of the second section of the stick, designed to receive the runner when the umbrella is extended, and with its ledge *p* prevent it from going too high, and with its pin *m* prevent the runner from falling. *v*, at the upper end of the first section of the stick, in fig. 4, is a spiral thread to which the top notch, as seen at *y y* in fig. 1, and which is made in the usual way, is secured. In fig. 1, *w* is a metallic cap, which also screws on to the end of the spiral thread *v* in fig. 4, and which fastens the cover securely between itself and top notch *y y*. In fig. 1, *x* is a ring passing through cap *w*, and designed to aid in distending the umbrella and in hanging it up when not in use. In figs. 4 and 8 is represented handle *b*; *ee* as open with the third section of the stick to which it is attached. In those figures, *f* is the third section of stick. The handle is of two parts, *ee* the upper, and *b* the lower. *ee* is screwed on to the outside of the lower end of section *f*. *aa* show a rebate cut in the lower side of *ee*, designed to receive the tip *c* of the rib *D*, as shown in fig. 4. The entire handle may be metallic, and its lower part *b* is convex on its lower surface, but concave on the upper, as shown at *g g*. The tube *zz* is firmly fastened to the lower part of handle *b*, and is inserted into the inside of the lower end of section *f*, in which is pin *n*, to which it is secured, and which moves freely vertically or laterally in the zigzag slot *i* as *b* is shut or opened or turned right or left. *dd* represent the outer rim of handle *b*, which, when it is shut, closes over the tips *c* and holds them in position, as shown in fig. 1, when folding up or distending the umbrella. Figs. 6 and 7 represent the runner *hh* and the tablet *k*, whose construc-

tion and attachment to the upper end of the second section of the stick has been already described. In fig. 7 the upper part of the runner is formed as usual, as shown at *h*. *o* is a slot to receive pin *m* of tablet *k*, fig. 6. *r r* are bevelled edges of slot *o* to receive more readily pin *m*. In fig. 6, *q* represents a ferrule extending vertically from *h* to 4, encircling runner *h h*, and moving laterally for a short distance back and forth, by manipulating the bead 4. The slot *o o* in it corresponds to slot *o'* in *h* of fig. 7, and is designed to receive pin *m* of tablet *k*. Fig. 3 represents stretcher *E*, which is metallic, and the rib, made of galvanized steel, which is composed of two sections, *A* and *B*, or three sections, *A*, *B*, and *D*, accordingly as a smaller or larger umbrella may be desired. The ribs are flat on the under side, and may be flat or rounded on the upper. Section *A* is attached to top notch *y y*, as shown in figs. 1 and 2, in the usual way. On the lower end of section *A* is a strong metallic clasp, 4, made either of the substance of the rib or firmly united to it, the edges of which bend under so as to embrace section of rib *B*, and permit it to slide smoothly through it. A portion of the lower edges of clasp 4 is bent outward and perforated, as at 13 13, figs. 2 and 9, so as to attach the cover thereto when desired. On the upper end of section *B* is clasp 3, whose edges are bent upward over section *A*, as seen at 15 15 in figs. 1 and 2, and yet so as to allow the clasp to slide smoothly over *A* to pin 12, carrying with it section *B* on the under side of *A*. On the under side of clasp 3 is firmly fastened a semicircular piece of metal, to which stretcher *E*, being bifurcated, is riveted, as shown at 2. On the lower end of section *B* is clasp 5, whose edges are bent under so as to embrace firmly section *D*, as shown at 5 5 in figs. 3 and 9, and yet to allow the movement of that section through the clasp from 8 to 5 in figs. 3 and 9. In those figures, *c c* on sections *D D* are strong metallic tips, which, when the umbrella is shut down, are fastened into the rebate *a a* by the rim *d d* of the handle *b*, as shown in figs. 1 and 4, and by which the ribs, with the stick, are shut up or distended. In fig. 9, at the point 16, is a hole where the cover is attached. 8, in same figure, is a shoulder, which should preferably be on both sides, preventing section *D* from sliding too far inward. 6, in same figure, is a head preventing it from sliding too far outward. In fig. 3, at the upper end of section *D*, opposite 6, is shown a small protuberance which represents a centre-punch made in the metal, designed, when *D* is fully distended, to slide into and fit closely in a cavity on the under side of clasp 5 at the point opposite the figure 7. This arrangement is designed to prevent section *D* from being forced back by the cover when the umbrella is extended. The same arrangement may be applied, and for the same purpose, to the under side of the clasp 3 of section *A*. Stretcher *E*, at 10, is attached to runner *h h* in the usual way, as shown in fig. 2.

The operation of the umbrella is as follows: Suppose it extended, as at fig. 2; press with the thumb and fore-finger on bead 4 of ferrule *q*, and turn it laterally to the right; this makes the vertical slot in the ferrule correspond with the slot in the runner, disengages the pin *m*, the runner falls, and the umbrella is shut down in the usual way. To fold it up, turn handle *b* laterally to the left about half round; this will disengage not only the handle, but will move the points of the tongues *g g*, in the interior of the stick, from the notches *s s* to the grooves *j j*, and leave the sections free to be shut up. Now pull out the handle *b* and its tube *z z* as far as they will go, say one-quarter of an inch; adjust the tips *c c* to the rebate *a a*, press the rim of handle *b* over the tips. Now turn handle to the right; this locks the handle. Place the cap of the umbrella on some solid substance, or, what is better, against your own body; grasp the umbrella with your left hand to prevent the ribs springing outward too much upon pressure. Now press steadily and gently with your right hand the handle *b* toward you, occasionally lifting outward from the machinery of the framework the material of the cover, until the stick and ribs will contract no more. The cover can now be gathered and folded on the outside by the hand, and, if need be, secured by an elastic cord. The umbrella now appears, with the exception of the cover, which is not shown in the drawing, as seen at fig. 1. To open it, place your left hand upon the umbrella at about the cap *w*, the thumb of that hand in the ring *x*. With your right hand grasp handle *b* and pull it steadily and gently out to the very farthest point of distension of the stick. Now encircling with your left hand the ribs near the tips, and clasping them tightly, turn with your right hand handle *b* about one-quarter of an inch to the left and pull out the handle; this releases the tips of the ribs. Now, grasping with your left hand cap *w*, with your right turn handle *b* to the right about half round; this locks the several sections of the stick by moving the ends of the tongues *g g* from the grooves *j j* to the notches *s s*. Now, carefully feeling for the runner with the left hand, turn the ferrule *q* slightly to the right to make its slot correspond with the slot in the runner. Then elevate the runner to the tablet *k*; this hoists and extends the umbrella. Now turn ferrule *q* slightly to the left; this fastens runner and ferrule on the pin *m* of tablet *k*, so that in this position they cannot possibly descend, and thus the extension of the umbrella is secured. If any of the ribs should be found not sufficiently distended, this can easily be effected by pulling them outward by the tips *c*. When it is desirable to construct an umbrella with but two sections of rib, those sections are made in all respects as *A* and *B*, with the exception that clasp 5 is omitted from the lower part of *B*, and that lower part is fashioned like the lower part of *D*, excepting shoulder 8 and tip *c*. In this case the stick is constructed with two or three sections, as seen at fig. 4, with the exception that the peculiar arrangement of handle *b e e* is omitted, and a simple ball or some other device is screwed on to the lower end of the second or third section of the stick. With the exception of the manipulation of the tips and the operation of the handle *b*, the umbrella with two sections of rib is operated the same as that with three.

What I claim as my invention, and desire to secure by Letters Patent, is—

1. The combination and arrangement of the extension stick and extension ribs, substantially as shown and described.
2. I claim the tongues *g g*, the grooves *j j*, the bands *l l*, the pins *t t*, the notches *s s*, and collars *u u*, as seen in figs. 4 and 5, by which the sections of the stick are made to glide equably, and locked and unlocked, and kept in position, all substantially as shown and described.

3. I claim the handle b e e , with all its parts, as seen in figs. 4 and 8, as described.
4. I claim the tablet k , with its pin m and ledge p , in fig. 6, the ferrule q , with its slots v o , adapted to move around the runner h h , as seen in same figure, and already described.
5. I claim the slot o' , with its bevelled edges r r in runner h in fig. 7.
6. I claim clasps 3, 4, and 5, as combined and arranged, of sections A, B, and D, as seen in figs. 3 and 9, the tip c , the shoulder 8 , and the centre-punch 6 , with cavity 7 for reception of centre-punch 6 .
7. I claim the wings 13 13 of clasps 4, adapted for attaching cover, as seen in fig. 9.
8. And I also claim, in combination with an umbrella stick, the sliding sections A, B, and D, substantially as described, by which the rib is shut up or distended.
